ATOMIZER

Carl Julius Lagerholm, Attleboro, Mass.

Application April 3, 1931. Serial No. 527,445

7 Claims. (Cl. 299—88)

This invention relates to atomizer construction and more particularly to an apparatus, adapted to be carried by the user, for vaporizing and spraying perfumes.

5 One of the objects of this invention is to provide a simple, rugged and compact construction for vaporizing perfume and the like. Another object of the invention is to provide a device of the character indicated that may be readily 10 operated with one finger. Another object of the invention is to provide an atomizer construction which may be quickly and easily sealed and unsealed. Another object of the invention is to provide an atomizer of the piston operated type in 15 which the operating mechanism may be locked and unlocked in a very simple and effective manner. Another object of the invention is to provide an atomizer of the piston operated type in which the piston has a definite range of movement during operation of the device, and is moved to a further position to seal the device. Other objects will be in part obvious or in part 20 pointed out hereinafter.

The invention accordingly consists in the features of construction, combinations of elements, and arrangements of parts, as will be exemplified in the structure to be hereinafter described, and the scope of the application of which will be indicated in the following claims.

30 In the accompanying drawing, in which is shown one of various possible embodiments of my invention,

Figure 1 is a side elevation of the device in closed condition, certain parts being shown in 35 central vertical section;

Figure 2 is a central vertical sectional view of the device shown in opened condition ready for manual operation;

Figure 3 is a top plan view;

40 Figure 4 is a fragmentary vertical sectional view on an enlarged scale of the piston rod and associated parts in elevated position, the section being taken on the line 4—4 of Figure 2;

Figure 5 is a fragmentary vertical sectional view 45 similar to Figure 4, showing the piston rod in depressed position;

Figure 6 is a horizontal sectional view taken on the line 6—6 of Figure 4;

Figure 7 is a top plan view of a modified form 50 of the device;

Figure 8 is a fragmentary vertical sectional view of the modified device, the section being taken on the line 8—8 of Figure 7; and

55 Figure 9 is a fragmentary side elevation of another modification.

Similar reference characters refer to similar parts throughout the several views of the drawing.

Referring now to the drawing and more particularly to Figures 1 and 2, there is generally indicated at 10 a container made preferably of 60 sheet metal and preferably elongated in transverse cross-section, as appears clearly from Figure 3. The top 11 of the container 10 has a substantially centrally positioned round opening with which is aligned a cylinder 12 in which a 65 piston generally indicated at 13 is to operate. As appears from Figure 2, the lower end of the cylinder 12 is closed, conveniently by the bottom member 12a of the cylinder 12. The upper end of the cylinder 12, which may be made of metal 70 tubing, is sealed, as by soldering, to the top member 11 of the casing 10.

The interior of the cylinder 12 is thus sealed off or separated from the interior of the container 10 and into the latter is placed the liquid 75 to be vaporized or sprayed, such as perfume.

In the top member 11 and to the right of the cylinder 12, as viewed in the drawing, is an opening for introducing the perfume or the like into the container 10; preferably this opening is formed 80 by an interiorly threaded collar 15 soldered to the top member 11 and adapted to be closed by the threaded plug generally indicated at 16, the latter having a threaded portion 16a and a knob-like operating portion 16b which projects above 85 the plane of the top 11 of the container 10, also a cylindrical guiding portion 16c.

Through the top member 11 and to the left of the cylinder 12, as viewed in the drawing, projects a metal tube 17 (see Figure 2), the tube 17 90 extending downwardly into the container 10 to a point in proximity to the bottom 14 thereof. The upper exposed end 17a of the tube 17 may be suitably shaped or restricted to form a nozzle or jet through which the liquid from the container 95 10 may be discharged in a manner more clearly described hereinafter. Adjacent to the jet 17a is a short tube 18 extending through the top 11, forming a vent to permit more convenient filling of the container with the liquid, allowing the 100 escape of air as the liquid is poured through the filling opening 15, and preventing the formation of a partial vacuum in the container 10 above the liquid during operation of the device, which partial vacuum might restrict the flow of liquid 105 through the tube 17.

Referring to Figures 1 and 2, a tube 19 extends from the lower or discharge end of the cylinder 12 upwardly through a plug of moldable metal 19a to the outside of the casing above the top member 110

11 thereof. The upper end of the tube 19 is bent sharply, the bend being located in the moldable metal 19a, and the upper extremity of the tube 19 constitutes a nozzle 19b, which, as clearly shown in Figures 1 and 2, is located in proximity to the upper end of the nozzle 17a, so that when the downward movement of the piston 13 takes place, a stream of air is blown out of the tube 19 and substantially across the nozzle 17a, thus drawing liquid upwardly in the tube 17 and causing the spraying or diffusion of the liquid as rapidly as it is drawn upwardly and out of the tube 17.

The piston 13 is adapted for manual actuation and is secured to the lower end of a plunger or piston rod generally indicated at 20 (Figures 2 and 4), the latter having a threaded lower end portion 20b adapted to receive a nut 22 and a washer 23 by means of which the piston proper 13a, taking the form of an inverted cup-shaped leather washer, is securely clamped. Preferably, also, a washer 13b is interposed between the leather piston proper 13a and the piston rod 20, so as to back up the piston proper 13a during its down stroke when the air in the cylinder 12 is expelled through the tube 19.

Referring now particularly to Figures 1, 2 and 4, the piston 20 includes a portion 20a which is non-circular in cross-section, preferably being square, as shown in Figure 6. This portion 20a extends through a cylinder head 25 which has an opening 25a of such size and shape as to permit reciprocation of the piston rod in it while preventing turning movement of the piston rod 20 with respect to the cylinder head 25. In order to facilitate manufacture of the cylinder head 25, it is preferably counterbored, as shown at 25b. The opening 25a is desirably square and at certain portions fits the portion 20a of the piston rod 20 closely, but sufficient clearance is desirably allowed to permit the ready passage of air between the piston rod and the cylinder head 25 in order to prevent back pressure upon the piston when it is being operated. Located in the cylinder 12 is a spring 26, which urges the piston 13 upwardly to the position shown in Figure 2, in which position the washer 13b abuts the cylinder head 25.

Referring now particularly to Figures 4 and 5, the portion 20a of the piston 20 has therein a longitudinal bore 28, the upper end of which is threaded at 29. Near the upper end of the portion 20a a transverse bore 30 extends through the piston rod 20 penetrating the bore 28. As actually shown in Figures 1 and 4, a corner of the square piston rod portion 20a is milled to form a flat surface 30a having a dihedral angular relationship with the sides of the portion 20a of 45 degrees, and starting from the milled portion 30a the bore 30 is drilled through the center of the portion 20a to the diagonally opposite corner of the portion 20a where the drill point just emerges without pushing the drill through to make a full diameter bore. This leaves an orifice 30b of irregular shape and of generally smaller width than the bore 30, there being guard portions 30c which hold a ball 31 from falling out of the bore 30 wherein it is located, but permit it to project from the corner of the piston rod portion 20a and also from the flat sides thereof. The bore 30 might be drilled perpendicular to a flat side of the piston rod portion 20a so far as certain features of the invention are concerned.

Still referring to Figure 4, a knob or operating member 32 has screw threads 33 adapted to fit the threads 29 in the bore 28 of the piston rod

portion 20a. This knob 32, which to all intents and purposes is an integral part of the piston rod 20 when the device is assembled, has a bore 34 therethrough extending from the top of the knob through the portion 35 which has the screw 80 threads 33. The knob 32 may have any attractive design and preferably includes a circular flange 36, between which and the top of the piston rod portion 20a is secured a flat portion 37 of a pressed metal cover 38, the flat portion 37 having a hole 39 therethrough which receives the threaded part 35 of the knob 32. Desirably a portion 37a is struck downwardly from the portion 37 forming a key which seats in a corresponding notch made in the upper surface of the piston portion 20a, as indicated in Figure 2.

Mounted for sliding movement in the bore 34 of the knob 32 is a pin 40, the lower end of which constitutes a piston-like portion 41. Above the piston portion 41 is a flange 42, and the flange 42 and the piston portion 41 are separated by an annular groove 43. In the bore 28 and below the piston portion 41 is a spring 44 which urges the pin 40 and its associated parts upwardly, forcing the flange 42 against the threaded portion 100 35 of the knob 32. In this position of the parts, as illustrated in Figure 4, the ball 31 is maintained in the bore 30 in such a position that it projects beyond the corner and sides of the piston portion 20a, while when the pin 40 is depressed, as shown in Figure 5, the ball 31, when pressure is exerted against it, moves into the large bore 28 by reason of the fact that the recess 43 is at that time in line with the bore 30. The upper surface of the knob 32 is desirably knurled, 105 as shown at 46, so as to permit the finger of a user of the device to grip the knob without slipping therefrom. Referring now to Figures 3, 4 and 5, preferably a groove 47 is formed in the upper surface of the knob 32, the center of the 110 groove 47 crossing the axis of the bore 34. Preferably also a notch 48 is formed in the upper end of the pin 40.

In the cover 38 is a piece of rubber or other soft material 50 which, when the cover is closed, forms 120 a stopper for the nozzles 17a and 19b and also for the tube 18, preventing the escape of fluid from the container 10. In order to secure the piece of rubber or other soft material 50 in position in the cover 38, a portion 50a thereof is clamped 125 by a metal clamp 50b which is affixed to the sides of the cover 38 by soldering.

Considering now the operation of the device, the parts, when in closed relation, assume the position shown in Figure 1, and at that time, the 130 pin 40 being in its upper position, the piston portion 41 holds the ball 31 projecting from the sides and corner of the piston rod portion 20a, as best illustrated in Figure 6. As illustrated in Figure 1, the ball 31 is at that time below the cylinder head 25 and in engagement with it, thus preventing the rise of the piston 13 and piston rod 20 by such engagement. All operating parts of the device are at this time sealed, and both nozzles and the vent 18 are closed, as clearly 140 shown in Figure 1.

When the user wishes to operate the device he holds it in one hand and passes the thumb nail or a finger nail along the groove 47 until it comes in contact with the upper end of the pin 40 or 145 the notch 48 therein. A slight downward movement of the finger nail depresses the pin 40 moving the groove 43 opposite the ball 31. As there is then nothing to back up the ball 31, the spring 26 in the cylinder 12 forces the piston upwardly, 150

the user holding his thumb or finger upon the knob 32 thereof and allowing it to rise as high as he desires. The finger nail being then taken from the pin 40, the pin moves upwardly under 5 the influence of the spring 44 placing the piston portion 41 again back of the ball 31 and forcing the ball through the opening 30b to the position shown in Figures 4 and 6. The user then reciprocates the entire piston with the finger, and 10 owing to the fact that the top of the pin 40 lies in the groove 47, there is no tendency to depress the pin 40 when he does so. The ball 31, when the piston 20 is being reciprocated, acts as a limiting stop, preventing the cover 38, which of 15 course rises and falls with the piston 20, from covering the nozzles 17a and 19b and the vent 18. The ball 31, when acting as a limiting stop to prevent re-locking of the device in closed position, engages the cylinder head 25 at the bottom 20 of the counterbore 25b.

Reciprocation of the piston rod 20 and the piston 13 forces air from the cylinder 12 through the tube 19 and from the nozzle 19b. The piston 13, cylinder 12 and operating mechanism constitute a pressure generator to spray the perfume contained in the container 10. The blast of air upon the top of the nozzle 17a draws liquid from the container 10 by aspiration and atomizes the liquid as it escapes from the nozzle 17a, the vent 30 18 preventing the formation of any vacuum in the container 10 irrespective of how much liquid is drawn therefrom at a given time.

When the user wishes to close the device again he depresses the piston 20 by forcing downwardly 35 the knob 32 and at the same time inserts a finger or thumb in the groove 47 depressing the pin 40. This brings the groove 43 opposite the ball 31 and the ball 31 passes by the cylinder head 25, whereupon release of the finger or thumb nail 40 from the pin 40 causes the ball 31 to move outwardly again under the influence of the spring 44 and the edge of the piston portion 41 which is forced upwardly, thus locking the piston 20 and the cover 38 in downward position, as shown 45 in Figure 1, in which position the piece of rubber or other soft material 50 closes the nozzles and the vent as described.

Referring now to Figures 7 and 8, a slightly modified construction is shown in which the cover 56 51 is of elongated form, as shown in Figure 7, and covers the entire top of the article. This cover may be made of sheet metal pressed into the form shown in Figures 7 and 8 and including a side wall 51a extending entirely around it. In the center of the top of the cover is a circular depression 52, 52 and in the center of the circular depression is a hole 53. The pin 40 extends through a flanged nut 54, the flange 54a of which fits in the depression 53. The nut has a screw-threaded 60 portion 54b engaging the threads 29 of the bore 28. A rather thick washer 55 is interposed between the underside of the cover 51 below the depression 53 and the top of the piston rod portion 20a. The other parts of the device shown 65 in Figures 7 and 8 may be the same as previously described in the case of Figures 1 to 6 inclusive.

In operating the modified construction shown 70 in Figures 7 and 8, the pin 40 may be depressed with a finger, thus releasing the cover 51, and then a pair of fingers placed on either side of the pin 40 and engaging the cover 51 may be used to reciprocate the piston 13, and the ball 31 will remain projecting from the hole 30b acting as a limiting stop for the downward movement of the piston and piston rod.

Referring now to Figure 9, another modified construction is shown in which the cover 56 covers slightly more than half the length of the top of the container 10 and may be shaped, in plan, similar to the outline of the top shown in Figure 3, being rounded at 57 concentric with the axis of the piston 20. The cover 56 has a skirt portion 58 extending all around it, the rounded portion 57, however, being of slightly less depth in order to allow clearance for the cylinder head 80 25. Also, preferably, the front of the cover 56 is cut away, as indicated at 59, so that the nozzles 19b and 17a will be cleared after a very limited movement of the piston rod 20 upwardly.

The polygonal portion 20a of the piston rod 20 abuts the underside of the cover 56 which may be of sheet metal, and the flanged nut 60, having a screw-threaded portion 61 with a bore therethrough, holds the cover 56 to the piston 20. The pin 40 extends through the bore in the nut 61, 90 and in other respects the parts of the embodiment shown in Figure 9 are as already described, the filling cap 16c being of slightly different shape having a screw slot 16y adapted to fit a coin.

The construction of Figure 9 is operated substantially as the other constructions, but it is noted that it may be operated with one finger which is placed against the pin 40 to release the device, then slid to the top of the cover 56 to reciprocate the piston, during which reciprocation the ball 31 acts as a limiting stop. When it is desired to replace the cover 56 in closed position, the finger is moved to the pin 40 again, and when the parts are closed, the finger may be slipped toward the front of the device, which automatically locks as the pin 40 springs upwardly.

It will thus be seen that there has been provided in this invention an apparatus in which the several objects hereinabove pointed out, together with many thoroughly practical advantages, are 105 successfully achieved. It will be seen that the apparatus is of compact and durable construction and of dependable action, and that it is well adapted to meet the conditions of hard practical use.

As many possible embodiments may be made of the above invention, and as many changes might be made in the embodiment above set forth, it is to be understood that all matter hereinbefore set forth, or shown in the accompanying drawing, is 115 120 to be interpreted as illustrative and not in a limiting sense.

I claim:

1. In a locking mechanism for a hand sprayer operating pump, in combination, a cylinder, a cylinder head for said cylinder, a piston in said cylinder, a piston rod for said piston passing through said cylinder head, there being a longitudinal bore in said piston rod, a pistonlike portion fitting in said longitudinal bore, a rodlike portion extending upwardly from said pistonlike portion, there being an annular groove in said rodlike portion above said pistonlike portion, a knob attached to the upper end of said piston rod, there being a longitudinal bore in said knob through which said rodlike portion extends, a spring located in said piston rod underneath the pistonlike portion, there being a lateral bore in the side of said piston rod, a ball substantially filling said last named bore, a shoulder on the under side of the cylinder 130 head, and a portion of the rodlike portion projecting upwardly above a part of the knob and constituting a pin for the operation of the locking mechanism, the depression of the pin allowing the ball to withdraw into the recess whereby 135 140 145 150

- it can bypass the shoulder on the cylinder head and release of the pin causing the spring in the longitudinal bore to force upwardly the piston-like portion thus projecting the ball outwardly 5 and, when the piston is down in the cylinder, locking the piston from upward movement therein.
2. In apparatus as claimed in claim 1, the combination with the parts therein specified, of a shoulder on the upper side of said cylinder head 10 to limit downward movement of the piston and piston rod when the ball is projected outwardly in the lateral bore by reason of the spring in the longitudinal bore of the piston rod and the pistonlike portion therein.
- 15 3. In a locking mechanism for a hand sprayer operating pump, in combination, a cylinder, a cylinder head for said cylinder, a piston in said cylinder, a piston rod for said piston passing through said cylinder head, there being a longitudinal bore in said piston rod, a pistonlike portion fitting in said longitudinal bore, a rodlike portion extending upwardly from said pistonlike portion, there being an annular groove in said rodlike portion above said pistonlike portion, a 20 knob attached to the upper end of said piston rod, there being a longitudinal bore in said knob through which said rodlike portion extends, a spring located in said piston rod underneath the pistonlike portion, there being a lateral bore in the side of said piston rod, a ball substantially 25 filling said last named bore, a shoulder on the upper side of the cylinder head, and a portion of the rodlike portion projecting upwardly above a part of the knob and constituting a pin for 30 the operation of the locking mechanism, the depression of the pin allowing the ball to withdraw into the recess whereby it can bypass the shoulder on the cylinder head and release of the pin causing the spring in the longitudinal bore to 35 force upwardly the pistonlike portion thus projecting the ball outwardly and, when the piston is up in the cylinder, preventing it from being forced downwardly beyond the point where the ball contacts with the shoulder.
4. In a locking mechanism for a hand sprayer operating pump, in combination, a cylinder, a piston in said cylinder, a spring underneath the piston, detent locking means to lock the piston downwardly in the cylinder against the 40 action of the spring, a piston rod extending upwardly from the piston, a knob on top of said piston rod, a pin passing through the knob and connected to the detent locking mechanism, and a groove in the top of the knob said groove bisecting said pin, whereby the pin may be operated by the finger nail to release the detent locking means, but when the finger or thumb is placed on the knob the pin will not be operated and the locking means will not be released.
- 60 5. In apparatus of the class described, in combination, a container for liquid to be sprayed, a pressure conduit, a pressure generator connected to said pressure conduit, means actuated by said pressure in the conduit arranged to discharge atomized liquid from said container, a movable member forming part of said pressure generator, and so constructed and arranged as to actuate said pressure generator thereby discharging liquid from said container, an annular member through which said movable member projects and in which said movable member slidably fits, a pin including a portion with a lateral recess said portion being in the movable member, a ball of a size to fit in said recess located in an opening in the wall of said movable member thus to hold said movable member in one position thereof, and a mounting for the pin to permit movement thereof whereby said ball may fit in said recess to release the movable member. 80
6. In apparatus of the class described, in combination, a container for liquid to be sprayed, a pressure conduit, a pressure generator connected to said pressure conduit, means actuated by said pressure in the conduit arranged to discharge atomized liquid from said container, an actuating member for said generator, means limiting the movement of said actuating member to a rectilinear path said member extending upwardly from said container, a manually engageable member forming part of said actuating member, a pin extending from the top of said manually engageable member and movable therein, a laterally recessed member connected to said pin, said recessed member being located in a bore in 100 said actuating member, there being a hole in the side of said actuating member, and a ball engageable through said hole with a part connected to the container to hold the actuating member in position and disengageable when the pin is moved to bring the recess opposite said ball. 105
7. In an atomizer, the combination with a cylinder, a plunger operating therein, a cylinder head for the cylinder, a fluid discharge tube, 110 a nozzle arranged at the discharge end of the tube, connections whereby atomized fluid is discharged from the nozzle upon movement of the plunger in one direction, and a cover for the nozzle mounted on the plunger, of means to hold the plunger in one position, means to release the plunger, an operating handle for the plunger having a groove, and a pin located in the groove connected to operate the means to release the plunger, whereby the plunger may be reciprocated by finger pressure the finger resting over the groove and without effect on the pin and released with a finger nail. 115
